UNITED STATES PATENT OFFICE.

JAMES ELMER RUFFNER, OF JEANNETTE, PENNSYLVANIA.

WASHING MACHINE.

Application filed January 25, 1927. Serial No. 163,452.

This invention relates to washing machines and it is primarily an object of the invention to provide a device of this kind especially designed and adapted for use in connection with articles for infant wear.

It is also an object of the invention to provide a device of this kind wherein the articles to be cleansed are effectively agitated in a manner and a cleansing fluid caused to circulate therethrough resulting in effective cleansing of the articles.

The invention consists in the details of construction and in the combination and arrangement of the several parts of my improved washing machine whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawing, wherein:—

Figure 1 is a view partly in section and partly in elevation illustrating a washing machine constructed in accordance with an embodiment of my invention, an associated support being fragmentarily indicated by broken lines;

Figure 2 is a sectional view taken substantially on the line 2—2 of Figure 1, with the support and a hose connection indicated by broken lines.

As disclosed in the accompanying drawing, my improved machine comprises a receptacle R of requisite dimensions and preferably formed in the fashion of a bucket, said receptacle being provided at its upper part with the diametrically opposed ears 1 to which a suitable bail is adapted to be attached. The side wall 2 of the bucket in relatively close proximity to its upper or open end is provided with the diametrically opposed openings 3, each of said openings being of a material length in a direction circumferentially of the wall 2. Each of these openings 3 is in communication with the upper portion of an exterior conduit 4 carried by the wall 2, said conduits 4 having their lower portions connected by a conduit 5 extending radially across the bottom 6 of the receptacle R and arranged exteriorly thereof.

The central portion of the conduit 5 is provided with a discharge opening 7 defined by a depending sleeve 8. The bottom 6 of the receptacle R at its axial center and at a point directly above the discharge opening 7 is provided with a drain opening 9 which is normally closed by the plug 10. The lower portion of the receptacle R is provided with an interior continuous shoulder 11 formed by an inserted ring or hoop 12 which provides a support for a perforated false bottom 14. This bottom 14 at its axial center is provided with an upstanding conoidal block 15 which provides a bearing for the inserted end portion of a dasher D. This dasher D comprises an elongated stem 16 provided at its lower portion with the oppositely directed paddles or blades 17 and the hub portion 18 of the blades in the outer face thereof is provided with a pocket or recess 19 which substantially snugly receives the block 15. By this means the dasher D is effectively maintained in applied position within the receptacle to facilitate its desired functioning upon rotation.

The upper portion of the stem 16 is suitably supported by the applied lid L for the receptacle. This lid L may be constructed in any manner desired. The false bottom 14 is spaced from the bottom 6 proper of the receptacle and in communication with such space 20 is a nipple 21 to which is adapted to be coupled a hose line 22 indicated by broken lines. This hose line is also adapted to be coupled to a water faucet of a bath fixture or other water supply under pressure.

In practice, my improved machine is placed within the opening of a toilet seat, commode or the like and the hose line 22 connected to the nipple 21 and to a bath tub faucet or other water supply under pressure. The articles to be cleansed are then placed within the receptacle R after which the water is turned on. The dasher D is then turned or rocked eight or ten times resulting in effective cleansing of all refuse from the articles. The water as it passes through the nipple 21 enters the space 20 and up through the perforated false bottom 14. As the water rises upwardly within the receptacle R it will carry the loosened refuse upwardly and as the water passes or discharges out through the openings 3 such refuse will be carried off and discharged through the opening 7 after passing through the conduits 4 and 5. After all of the refuse

has been carried off, the flow of water openings through the nipple 21 is closed whereupon soap or other cleansing agent is placed within the water remaining in the receptacle

5 R. The dasher D is then turned or rocked a few times. After this action the water is again turned on to pass through the nipple 21 into the space 20 and upwardly of the receptacle R and out through the openings 10 3. This results in an effective rinsing of the articles.

The dasher D may be rotated or rocked in any manner preferred but, as herein disclosed, I provide the upper end portion of 15 the stem 16 with an operating handle 23.

The bottom 6 of the receptacle has depending therefrom, and secured thereto in any desired manner, the blocks 23. These 20 blocks 23, as herein disclosed, are diametrically opposed and in quartered relation to the conduit 5 with the bottom faces of the blocks 23 substantially coplanar with the under face of the conduit 5. By this means the device in its entirety is firmly placed 25 upon the toilet seat or the like.

From the foregoing description it is thought to be obvious that a washing machine constructed in accordance with my invention is particularly well adapted for use 30 by reason of the convenience and facility with which it may be assembled and operated, and it will also be obvious that my invention is susceptible of some change and modification without departing from the 35 principles and spirit thereof and for this reason I do not wish to be understood as limiting myself to the precise arrangement and formation of the several parts herein shown in carrying out my invention in practice except as hereinafter claimed.

I claim:

1. A washing machine comprising a receptacle having substantially opposed openings in the upper portion of its side wall, 45 conduits carried by such side wall of the receptacle and leading downwardly from the openings, another conduit extending across the bottom of the receptacle and with which the first named conduits communicate, the 50 central portion of the last named conduit being provided with a discharge opening, a dasher working within the receptacle, and means for admitting liquid under pressure within the lower portion of the 55 receptacle to provide the continuous upward movement of the liquid in the receptacle, said liquid rising within the receptacle carrying off through the conduits matter loosened from the articles being cleansed 60 within the receptacle.

2. A washing machine comprising a receptacle having substantially opposed openings in the upper portion of its side wall, 65 conduits carried by such side wall of the receptacle and leading downwardly from the

openings, another conduit extending across the bottom of the receptacle and with which the first named conduits communicate, the central portion of the last named conduit being provided with a discharge opening, a 70 dasher working within the receptacle, the bottom of the receptacle being provided with a drain opening, means for closing such drain opening, and means for admitting liquid under pressure within the lower 75 portion of the receptacle to provide the continuous upward movement of the liquid in the receptacle, said liquid rising within the receptacle carrying off through the conduits matter loosened from the articles being 80 cleansed within the receptacle.

3. A washing machine comprising a receptacle having substantially opposed openings in the upper portion of its side wall, 85 conduits carried by such side wall of the receptacle and leading downwardly from the openings, another conduit extending across the bottom of the receptacle and with which the first named conduits communicate, the central portion of the last named conduit being provided with a discharge opening, a dasher working within the receptacle, a perforated false bottom within the receptacle spaced from the bottom proper of the receptacle, and means for discharging liquid under pressure within the receptacle below the false bottom to provide the continuous upward movement of the liquid in the receptacle, said liquid rising within the receptacle carrying off through the conduits matter loosened from the articles being cleansed 90 within the receptacle.

4. A washing machine comprising a receptacle having substantially opposed openings in the upper portion of its side wall, 100 conduits carried by such side wall of the receptacle and leading downwardly from the openings, another conduit extending across the bottom of the receptacle and with which the first named conduits communicate, the 105 central portion of the last named conduit being provided with a discharge opening, a dasher working within the receptacle, a perforated false bottom within the receptacle spaced from the bottom proper of the receptacle, said false bottom providing a support for the dasher, and means for discharging liquid under pressure within the receptacle below the false bottom to provide the continuous upward movement of the liquid 110 in the receptacle, said liquid rising within the receptacle carrying off through the conduits matter loosened from the articles being 115 cleansed within the receptacle.

5. A washing machine comprising a receptacle having substantially opposed openings in the upper portion of its side wall, 120 conduits carried by such side wall of the receptacle and leading downwardly from the openings, another conduit extending across 125

the bottom of the receptacle and with which the first named conduits communicate, the central portion of the last named conduit being provided with a discharge opening, a 5 dasher working within the receptacle, a perforated false bottom within the receptacle spaced from the bottom proper of the receptacle, an upstanding block carried by the central portion of the false bottom, the 10 dasher having a recess receiving such block when the dasher is in working position, and means for discharging liquid under pressure within the receptacle below the false bottom to provide the continuous upward movement 15 of the liquid in the receptacle, said liquid rising within the receptacle carrying off through the conduits matter loosened from

the articles being cleansed within the receptacle.

6. A washing machine comprising a receptacle, a discharge conduit leading from the upper portion of the receptacle and discharging at a point therebelow, means for admitting fluid under pressure within the lower portion of the receptacle to effect a continuous upward flow of the fluid within the receptacle for discharge through the conduit, and means for agitating within the receptacle the articles to be cleansed, the rising of the fluid within the receptacle 30 carrying off matter freed from the articles.

In testimony whereof I hereunto affix my signature.

JAMES E. RUFFNER.
